UNITED STATES PATENT OFFICE

RUSSELL A. PICKENS, OF FAIR LAWN, NEW JERSEY, ASSIGNOR TO SERVEL INC., OF NEW YORK, N. Y., A CORPORATION OF DELAWARE

DESIGN FOR A CABINET

Application filed November 11, 1930. Serial No. 37,627. Term of patent 3½ years.

To all whom it may concern:

Be it known that I, RUSSELL A. PICKENS, a citizen of the United States, residing at Fair Lawn (Radburn), in the county of Bergen and State of New Jersey, have invented a new, original, and ornamental Design for a Cabinet, of which the following is a specification, reference being had to the accompanying drawing, forming a part thereof.

The figure is a perspective view of a cabinet showing my new design.

I claim:

The ornamental design for a cabinet, as shown.

RUSSELL A. PICKENS.
